UNITED STATES PATENT OFFICE.

BASIL H. SAVAGE, OF SAN FRANCISCO, CALIFORNIA, ASSIGNOR, BY MESNE ASSIGNMENTS, TO MICHAEL J. SAVAGE, OF LOS ANGELES, CALIFORNIA.

WATER-CHARGING APPARATUS.

Application filed April 13, 1922. Serial No. 552,367.

To all whom it may concern:

Be it known that I, BASIL H. SAVAGE, a citizen of the United States of America, and a resident of the city and county of 5 San Francisco and State of California, have invented a new and useful Water-Charging Apparatus, of which the following is a specification.

My invention relates to devices for charging water with carbonic acid gas and dispensing the charged water. One of the objects of the invention is the provision of 10 an apparatus into which plain water may flow as rapidly as it is drawn off thru a draught head and which is charged with 15 carbonic acid gas while in the apparatus.

My invention possesses other objects and features of advantage, some of which, with the foregoing, will be set forth in the following description of my invention. It is to be understood that I do not limit myself to the showing made by the said description, as I may adopt variant forms of my 20 invention within the scope of the claim.

Referring to the drawings, Fig. 1 is a 25 vertical sectional view thru my apparatus. Fig. 2 is an elevation of a portion of the draught head showing the valve seat. Fig. 3 is an elevation of the end of the plug 30 valve. Fig. 4 is a front elevation of the draught head, portions thereof being sectioned.

Broadly stated, my invention comprises a tank into which water to be charged and 35 charging gas may flow. The upper end of the tank is provided with a discharge passage terminating in a draught head embodying a valve for controlling the flow of charged water from the tank, and also for controlling the flow of charging gas to the 40 tank. The valve is so arranged that the gas supply passage is open only when the charged water discharge passage is closed and is closed when the charged water 45 discharge passage is open. The unitary valve performing these functions is controlled by a single draught arm. When the draught arm is moved to draw charged water from the tank, the carbonic acid gas flow is interrupted and fresh water enters the tank to replace the charged water withdrawn. With the recovery movement of the draught 50 arm to stop the flow of charged water the carbonic acid gas is again turned on to fully charge the diluted mixture in the tank.

Suitable check valves are provided in the gas and water supply passages to prevent back flow from the tank, and suitable means are also provided for cooling the charged 60 water.

More particularly, my device comprises a base plate 2 and a top plate 3 between which a cylindrical shell 4 is secured by bolts 6. Gaskets 7 are interposed between the cylindrical shell and the ends in order to provide a tank secure against leakage and capable of withstanding some degree of pressure. Connected into the bottom of the tank is a water supply pipe 8 in which is a check valve 9 to prevent any back 70 flow.

Extending from the top plate 3 is a boss 11 enclosing the passage 12, and a draught head 13 embodying a plug valve 14, controlled by the draught arm 16, is mounted 75 on the boss. The base plate 2 is also formed with a boss 17 enclosing a passage 18 provided with a check valve 19 thru which gas enters the tank. The gas supply passage 18 is connected by a conduit 21 with 80 a port 22 opening on the face of the valve seat in the draught head and a similar port 23 closely spaced to port 22 marks the inner end of the conduit 24, the outer end of which terminates in a nipple 26 85 for connection with any suitable source of gas. The discharge passage 12 also opens on the valve seat in the port 27.

The plug valve 14 is provided with a recess 28 adapted to be registered with the 90 two ports 22 and 23, to connect the gas passages. Ports 31 and 32 in the flat face of the plug valve are also provided, and open in ports 33 and 34 respectively on the lateral face of the valve. Either of the ports 31 and 32 are adapted to be registered with the port 27 at which time the corresponding port 33 or 34, as the case may be, is in register with the port 36 which 95 marks the opening of the discharge passage 37 in the nozzle of the draught head. The ports 33 and 34 preferably vary in size so that at the option of the operator a stream of small or large volume may be projected from the nozzle.

The arrangement of the ports will be obvious from an inspection of Figs. 2 and 3 and is such that with the draught arm 16 in the position A, shown in Fig. 1, the recess 28 in the valve is in register with the 100 105 110

ports 22 and 23 thus allowing gas to enter the charging tank. In this position the port 27 is covered. In order to draw charged water the draught arm is pulled forward, 5 to position B, first covering the ports 22 and 23 and cutting off the flow of charging gas, and next registering the port 27 with the port 32, thus permitting a relatively 10 large volume stream of charged water to escape. By moving the draught arm backwardly to position C, the port 31 is registered with the port 27 and a stream of higher velocity and smaller volume is then 15 projected from the nozzle of the draught head.

While the charged water is flowing from the draught head the gas is shut off from the pressure tank and fresh water is entering the bottom of the tank to replace the 20 charged water withdrawn from the top. With the recovery movement of the draught arm to position A the discharge of charged water is stopped and the gas again turned on so that the diluted mixture in the tank 25 may be again brought up to the saturation point.

A double walled shell 38 embodying a layer of heat-insulating material preferably surrounds the tank, providing an annular

space 39 in which ice or any other suitable 30 cooling agent may be placed. A flange 41 on the base plate 2 provides a suitable base for the apparatus to stand on, and an insulated cover 42 closes the top of the shell. As a matter of appearance I prefer to 35 enclose the conduits 21 and 24 in a tube 43.

In order to perfect the joint between the plug valve and its seat, I prefer to form the end face of the plug of a rubber gasket, 40 prevented from rotation by the engagement 45 therein of short studs 44 projecting from the plug.

I claim:

In an apparatus for charging water with 45 gas, a charging tank, a passage for connecting said tank to a source of water, a discharge passage for the charged water opening from the top of the tank, a valve for controlling the flow of charged water arranged in said passage, a passage connecting a source of gas to said valve seat, and a passage extending from said valve seat to the bottom of said tank, said valve being recessed to connect said last two passages 50 when the discharge water passage is closed. 55

In testimony whereof, I have hereunto set my hand.

BASIL H. SAVAGE.
